QUICK DETACHABLE STARTER MOUNT

Richard E. Sears, Shaker Heights, Ohio, assignor
to Jack & Heintz Precision Industries, Inc.,
Cleveland, Ohio, a corporation of Delaware

Application August 3, 1948; Serial No. 42,317

1 Claim. (Cl. 123—179)

1

This invention relates in general to starters for internal combustion engines and more particularly to means for mounting the starter on the engine for cranking the engine and is a continuation in part of my co-pending application, Serial No. 706,457, for Quick Detachable Starter Mount, filed October 29, 1946, now Patent No. 2,506,239.

In aircraft engines, as stated in my co-pending application, it is desirable and usual practice to provide means for detachably securing the starter to the engine so that the forward end of the starter extends into the engine crankcase and to have complementary adjacent ratchet starter and engine crankshaft jaws that are normally disengaged with means in the starter to effect engagement and disengagement of the jaws. The usual practice is to provide the starter with a mounting flange with a series of holes to receive bolts for fastening the flange to the engine as the forward end of the starter extends into the crankcase. The tightening and loosening of these bolts is time consuming and it is difficult to insure uniform tightness of the bolts in assembly. Moreover, due to inaccessibility in many aircraft, installation and removal of the starter is either so difficult or impossible that some other engine accessories must be removed for starter installation, adjustment or removal.

In my co-pending application there is disclosed a quick detachable mount that involves only the manual tightening or loosening of a single bolt to effect starter installation, adjustment or removal. Moreover, it discloses an automatic spring operated locking means for locking the bolt in any adjusted position.

The present invention has to do with improvements over the disclosure of my co-pending application.

It is an object of the present invention to provide an improved automatic locking means for the single bolt attaching and detaching means. Briefly, the locking means may include a plate normally spring-pressed upwardly to engage the polygonal bolt head to prevent its turning. When it is desired to manually turn the bolt by a socket wrench, a downward pressure on the locking plate, against the action of the springs, pushes the plate out of such locking engagement and permits the wrench to turn the bolt. However, I have found that operators, in applying the socket wrench onto the bolt head, have a tendency to turn the bolt without first pressing far enough downwardly to be sure that the plate is out of locking engagement with the bolt. As a result, the plate is sometimes damaged or broken. My

present invention includes means to prevent such occurrence and includes a second plate on top of the locking plate. The top plate has a central aperture to loosely encircle the bolt head and normally lie flush with the top of the bolt head. The purpose is to render it necessary for the operator to push the top plate down far enough to obtain a grip on the bolt head which insures the lowering of the locking plate down far enough to be out of engagement with the bolt head.

With the foregoing and other objects in view, the invention resides in the combination of parts and in the details of construction hereinafter set forth in the following specification and appended claim, certain embodiments thereof being illustrated in the accompanying drawings, in which:

Figure 1 is a fragmentary view of an aircraft engine starter partly in side elevation and partly in section and a portion of the engine crankcase wall in section as well as the complementary securing screw threads on the engine crankcase and starter casing with the single bolt for starter installation and removal;

Figure 2 is a fragmentary view in top plan of the starter housing showing the assembling bolt and locking means therefor; and

Figure 3 is a view in section taken along line 3—3 of Figure 2, showing the assembling bolt and locking means therefor.

Referring more particularly to the drawings, the starter housing is generally indicated at 1 and the engine crankcase at 2. In conventional practice the forward, or right, end of the starter as viewed in Figure 1, would be provided with an enlarged mounting flange with a series of bolt holes to receive bolts to extend therethrough for locking the flange to the engine casing. The installation, adjustment and removal of starters in such a manner is time consuming and many times difficult, if not impossible, because of inaccessibility without removing other aircraft engine accessories.

Therefore, in the present invention the engine crankcase may be provided with a ring gear 3, rigid with the crankcase 2, and having female spiral threads to be engaged by similar male spiral threads 5 of a gear adapter 6 which abuts the inner shoulder of a mounting plate 4 secured by bolts 26 to the starter housing. To assist in mounting the starter, a series of screw bolts 27 are embedded in the crankcase to extend outwardly through the radial flange of ring gear 3. On each bolt 27 is a threaded sleeve 28 that extends through a hole in the mounting plate 4 to position the starter and prevent its turning.

With such an assembly, it is readily seen that a manual rotation of the pinion 9 in one direction forces the gear adapter 6 to rotate inwardly in the ring gear 3 which draws the starter, with its engine cranking jaw 29, into the crankcase, to the right, by outward pressure of the gear adapter 6 on the mounting flange 4, and a similar manual rotation of the pinion in the opposite direction withdraws the starter from the crankcase, to the left.

For the purpose of providing a simple single control means for so rotating and so installing, adjusting and removing the starter, the starter housing is provided with an angularly extending bore 7 in its wall to receive a bushing 8 in which is removably secured a manually rotatable pinion 9. This pinion is provided with bevelled teeth 10 to engage similar teeth 11 on the inner end of the gear adapter 6. Thus a manual turning of pinion 9 physically moves the starter into or out of the engine crankcase according to the direction of manual rotation of the pinion.

Assuming the starter jaw 29 to be a right hand jaw, the spiral male threads 5 on the gear adapter and the mating female threads on the ring gear 3 are left hand threads, or if the jaw 29 is a left hand jaw, the mating threads are made to be right hand threads.

In my co-pending application, as in my present application, there is disclosed an automatic locking means for locking the pinion in any adjusted position, in the present application best shown in Figures 2 and 3. In greater detail the pinion has a pivot bearing point 30 to engage a corresponding extension of bore 7. The pinion has a reduced diameter portion 12 to receive a packing ring 13. Loosely fitting over the pinion is a plate 14 apertured to receive the pinion 9 and a pair of ordinary screw mounting bolts 15 and 16 screwed to the starter housing. Above plate 14 is a second plate 17 provided with usual apertures to receive bolts 15 and 16. Above plate 17 are washers 18 and 19 and securing and tightening nuts 20 and 21 on bolts 15 and 16, respectively. This upper plate 17 has a central dodecagonal aperture 22 through which the hexagonal bolt head 23 of pinion 9 protrudes. An application of a wrench to effect turning of the nut 23, and hence the pinion 9, and the simultaneous downward pressure with the wrench upon plate 17 against the action of compression coil springs 24 and 25, brings the dodecagonal aperture 22 out of registry with the hexagonal bolt head 23 and permits the latter to be turned in either direction. Release of manual downward pressure on plate 17 permits springs 24 and 25 to restore registry between the hexagonal bolt head 23 and the dodecagonal aperture 22, which latter automatically and effectively locks bolt head 23 against rotation in either direction.

An improvement over my co-pending application in this regard includes the provision of an upwardly bowed plate 31 superimposed upon plate 17 and held in place by the same tightening nuts 20 and 21 that hold plate 17 in place.

The upwardly bowed portion of plate 31 has its upper surface flush with the top of the bolt head and is provided with a central aperture 32 large enough to leave ample clearance about the bolt head. The bowed portion is also high enough to prevent engagement of the bolt head by a socket wrench until downward pressure on plate 31 is exerted, and consequently on plate 17, against the action of springs 24 and 25, to force plate 17 out of locking engagement with the bolt head. In this manner, the bolt head is free to be manually turned only after the locking plate 17 is removed from locking engagement with the bolt head. In the absence of plate 31, it would be easily possible for the operator to manually turn the bolt while locked by plate 17, resulting in the damaging or breaking of the locking plate.

From the foregoing, it will be seen that there has been provided a simple and efficient means whereby an engine starter may be quick detachably secured to an engine for engine cranking purposes and insured against loosening during the cranking operation, and also an automatic locking means that effectively locks the starter in any desired adjusted position without interference in the manual installation, adjustment or removal of the starter from the engine and which is foolproof against breakage by inadvertent adjustment of the single bolt installation means.

I claim:

In combination an engine and a starter therefor both of which have a housing, a rotatable starter jaw, means for securing, adjusting and detaching said starter and engine housings, said housings having complementary engaging threaded members, an internal gear carried by said starter housing, a manually rotatable polygonally headed pinion extending through the starter housing and engaging said internal gear to rotate the latter in either direction to move said starter housing into or out of said engine, automatic locking means resiliently urged upwardly to normally lock said pinion head in any adjusted position, said locking means comprising a polygonally apertured plate resiliently urged upwardly to engage said pinion head in locked relation, a second plate superimposed upon said locking plate having a central aperture to surround said pinion head with clearance and having its upper surface normally flush with the top of said pinion head to preclude manual turning of said pinion until both of said plates have been manually forced downwardly to bring said locking plate out of locking engagement with said pinion head.
